UNITED STATES PATENT OFFICE.

FRANK COSS, OF GREENCASTLE, INDIANA.

RECORD-CABINET.

1,253,008.

Specification of Letters Patent.

Patented Jan. 8, 1918.

Application filed May 14, 1917. Serial No. 168,404.

To all whom it may concern:

Be it known that I, FRANK Coss, a citizen of the United States, residing at Greencastle, in the county of Putnam and State of Indiana, have invented a new and useful Record-Cabinet, of which the following is a specification.

It is the object of my invention to provide a cabinet for phonograph records, whereby the records may be stored compactly and protected from injury and yet each record is easily found and any record may be withdrawn from the cabinet with ease; and to do this by a structure which is simple and inexpensive in construction and efficient in operation.

The accompanying drawings illustrate my invention. Figure 1 is a front elevation of a record cabinet embodying my invention, showing it in connection with a standard talking machine; Fig. 2 is a vertical section through the record cabinet, taken parallel to the planes of the stored records; on the line 2—2 of Fig. 3; Fig. 3 is a partial plan 25 of the record cabinet with the ceiling piece removed and a partial section on the line 3—3 of Fig. 2; Fig. 4 is a partial perspective view of two of the partitions with their associated swinging leaves; Fig. 5 is a perspective view of the removable index board; Fig. 6 is a partial front elevation of such index board and the associated discharge keys below it; Fig. 7 is a similar front elevation of a slightly different form of index board; 35 and Fig. 8 is a partial perspective view of two of the discharge keys and their mounting.

My record cabinet may be embodied in any suitable structure, such as in combination with a talking machine, as shown in Fig. 1, and may consist of any desired number of tiers, two tiers being shown, the record-holding compartment conveniently being provided with the usual doors 10. Each 40 record-holding tier has a floor 11 which is inclined forwardly and downwardly, so that the records when released will roll forward by gravity. They are prevented from rolling entirely out by a stop piece 12 extending 45 transversely of the records and elevated slightly above the floor 11 at its forward edge, so as to stop the record in a position where it can readily be grasped by the person desiring to remove it. Each record is 50 located in a separate compartment, in which it is held on edge, these compartments being

provided by sheet metal plates 13 set in saw kerfs in the floor 11 and the ceiling 14. Each partition plate 13 is provided on one face with a fabric covering 15, which extends around the forward edge of such partition plate and covers the opposite face of a swinging leaf 16 so as to provide a hinge for such swinging leaf and a protecting covering to prevent scratching of the records by the metal of either the partition or the swinging leaf. Each partition 13 is notched at the front upper corner and is provided with a leaf spring 17 which projects through such notch against the side of the associated 60 swinging leaf 16 so as to force the rear edge of such swinging leaf toward the fabric-covered side of the adjacent partition. Thus the swinging leaf 16 forms a spring gripping device for holding the record in the 65 compartment into which said swinging leaf projects, so that until such spring gripping device is released the record will not roll forward along the inclined floor 11. Preferably, an extension of the fabric 15 projects 70 from the free edge of each swinging leaf 16 to the adjacent face of the partition 13 on which such swinging leaf is mounted, as is clear from Figs. 2 and 3, which extension 18 has sufficient slack so that it does not interfere with the swinging of the leaf, but 75 prevents a record which may be pushed into the compartment too far from being caught behind such swinging leaf.

In order to release a record 19 so that it 80 may roll forward along the floor 11, the swinging leaf 16, which normally holds such record, is swung against its associated spring 17 so as to separate it from the record which it holds. This swinging is obtained by 85 wedge-shaped discharge keys 20, one of which projects into the upper end of each record compartment between the swinging leaf 16 and the partition toward which the spring 17 pushes it, so that by pushing in 90 such wedge key the swinging leaf is moved against its spring to release the associated record 19. The second record from the bottom in Fig. 3 is shown released. Each release key is conveniently made of sheet 95 metal of the form shown in Fig. 8, with its wedge-shaped end projecting rearwardly from the lower end of the rear leg of an inverted U-shaped portion 21, and the release keys for all the compartments of a tier are 100 arranged in a horizontal row over a cross bar 22 (Fig. 8) notched on its upper surface 105

to receive the bases of the U-shaped portions 21 so that the rear leg of such U-shaped portion forms a stop to limit the forward movement of the key and the front leg forms a thumb piece, between which and the cross piece 22 a compression spring 23 tending to push the key forward is mounted. The keys are held in place in their notches in the cross piece 22 by a cover piece 24.

10 Above each row of keys 20 I preferably provide a removable index board 25, which is directly above the key-cover piece 24 and may take various forms, such as shown in Figs. 5 and 6, or as shown in Fig. 7. In 15 Figs. 5 and 6, the ends of this index board are provided with guide slots 26, which slide over projecting pins 27 from the uprights 28 at the sides of the cabinet, so that the index board may be slid in and out. In the 20 form shown in Fig. 7, the index board has a notch at one end to fit over a screw head 29 and a notch at the other end to coöperate with a spring catch 30, so that to remove the index board it is first swung from the 25 full line position to the dotted line position. The top face of the index board is provided with a suitable record surface, such as a layer 31 of celluloid, which is ruled to provide spaces in the planes of the various records 30 compartments, each space being directly over the associated key 20. The title of the record which is to go into any compartment is written in the corresponding space on the index board, so that the title of the record 35 appears directly over the release key which releases that record, as is indicated in Fig. 3.

In order to obtain any desired record, it 40 is located by its title on the index board, and the corresponding key 20, directly below that title, is pushed in. This pushes aside the 45 swinging leaf 16 which holds that record in its compartment, and allows such record to roll forward along the inclined floor 11 until stopped by the stop piece 12, in which position it can readily be grasped and withdrawn by hand. To replace a record, it needs only to be shoved into its compartment, where it 50 is held automatically by the swinging leaf 16 in such compartment.

55 I claim as my invention:

1. A record cabinet, comprising a casing having a forwardly slanting floor, a stop member at the forward part of such floor, a plurality of vertical partitions providing individual compartments for record disks between them, and releasable laterally-acting spring-pressed members coöoperating with said partitions for holding record disks in the compartments formed thereby.

60 2. A record cabinet, comprising a casing having a forwardly slanting floor, a plurality of vertical partitions providing individual compartments for record disks between them, and releasable laterally-acting 65 spring-pressed members coöoperating with

said partitions for holding record disks in the compartments formed thereby.

3. A record cabinet, comprising a casing having a forwardly slanting floor, a plurality of vertical partitions providing individual compartments for record disks between them, a swinging leaf mounted at the forward end of each partition and spring-pressed toward the adjacent partition to form a gripping member to hold a record disk in the compartment between such two partitions, and a series of discharge keys for separating the respective swinging leaves from the partitions toward which they are pressed so as to release the record disks. 75

4. A record cabinet, comprising a casing having a forwardly slanting floor, a plurality of vertical partitions providing individual compartments for record disks between them, a swinging leaf mounted at the forward end of each partition and spring-pressed toward the adjacent partition to form a gripping member to hold a record disk in the compartment between such two partitions, and a series of discharge keys for separating the respective swinging leaves from the partitions toward which they are pressed so as to release the record disks, 80 each of said keys including a wedge-shaped member mounted so that it can be pushed in between the associated swinging leaf and the partition toward which it is spring-pressed. 85

5. A record cabinet, comprising a casing having a forwardly slanting floor, a plurality of vertical partitions providing individual compartments for record disks between them, a swinging leaf mounted at the forward end of each partition and spring-pressed toward the adjacent partition to form a gripping member to hold a record disk in the compartment between such two partitions, a series of discharge keys for separating the respective swinging leaves from the partitions toward which they are pressed so as to release the record disks, and a fabric covering on the record-engaging faces of said partitions and swinging leaves, such fabric covering forming the hinge mounting between the leaves and the partitions on which they are respectively mounted. 100

6. A record cabinet, comprising a casing having a forwardly slanting floor, a plurality of vertical partitions providing individual compartments for record disks between them, a swinging leaf mounted at the forward end of each partition and spring-pressed toward the adjacent partition to form a gripping member to hold a record disk in the compartment between such two partitions, a series of discharge keys for separating the respective swinging leaves from the partitions toward which they are pressed so as to release the record disks, and 110

a fabric covering on the record-engaging faces of said partitions and swinging leaves.

7. A record cabinet, comprising a casing having a forwardly slanting floor, a plurality of vertical partitions providing individual compartments for record disks between them, a swinging leaf mounted at the forward end of each partition and spring-pressed toward the adjacent partition to 10 form a gripping member to hold a record disk in the compartment between such two partitions, a series of discharge keys for separating the respective swinging leaves from the partitions toward which they are

pressed so as to release the record disks, and 15 a fabric covering on the record-engaging faces of said partitions and swinging leaves, said fabric having a rearward extension beyond the rear edge of each swinging leaf, which edge is attached to the adjacent face 20 of the partition on which such swinging leaf is mounted.

In witness whereof, I have hereunto set my hand at Indianapolis, Indiana, this 9th day of May, A. D. one thousand nine hundred and seventeen. 25

FRANK COSS.
